UNITED STATES PATENT OFFICE.

GEORGE M. SCROGGS, OF NEW ORLEANS, LOUISIANA.

ANTISEPTIC LINING FOR MOUTHPIECES.

No. 914,194.

Specification of Letters Patent.

Patented March 2, 1909.

Application filed December 26, 1908. Serial No. 469,246.

To all whom it may concern:

Be it known that I, GEORGE M. SCROGGS, citizen of the United States, residing at New Orleans, in the parish of Orleans and State 5 of Louisiana, have invented new and useful Improvements in Antiseptic Lining for Mouthpieces, of which the following is a specification.

My invention relates to detachable anti- 10 septic linings for telephone mouthpieces; and it consists in the peculiar and advantageous lining hereinafter described and claimed.

In the drawings, accompanying and forming 15 part of this specification: Figure 1 is a view, partly in section and partly in elevation, illustrating the lining constituting the best, known embodiment of my invention, as properly positioned relative to the 20 mouthpiece of a conventional telephone fixture. Fig. 2 comprises disconnected views of the parts comprised in my novel lining.

Similar letters designate corresponding 25 parts in both views of the drawings, referring to which:

A is a mouthpiece which is shown as that of an ordinary telephone apparatus, and B, C and D are the outer member, the inner member, and the absorbent body, respectively, of the lining forming the subject of 30 my invention.

The outer member, B, of the improved 35 device, is made quite thin of metal, hard rubber or other material consonant with its purpose, and is exteriorly and interiorly tapered from a point adjacent its outer end to its inner end. At its said outer end the member B is provided with a circumferential flange b, which affords a shoulder c designed 40 to bring up against the outer end of the mouthpiece A, Fig. 1, with a view of limiting the inward movement of the lining when the same is applied to the mouthpiece. Exteriorly the outer member B is threaded at its 45 outer end, as indicated by d, for a purpose hereinafter set forth.

As shown in Fig. 1, read in connection 50 with Fig. 2, the inner member C of the lining is exteriorly and interiorly tapered correspondingly to the tapered portion of the outer member B. Said inner member, however, differs from the outer member in that its tapered portion is foraminous—i. e., is provided with closely arranged transverse 55 apertures e, the office of said apertures being

to permit disinfecting or antisepticizing fumes to pass freely from the absorbent body D to the interior of the telephone mouthpiece A. Said inner member C terminates at its outer end in a forwardly directed flange 60 f, and this latter is interiorly threaded, as indicated by g, to engage the exterior thread d of member B, after the manner shown in Fig. 1. It will also be observed by reference to the drawings that the member C carries 65 resilient clamps h, which are preferably fixed to the outer side of the member, by brazing or otherwise, and are arranged to extend forwardly at intervals and to grasp the outer portion of the mouthpiece A so as to de- 70 tachably retain my lining in the said mouthpiece in such manner that there is no liability of the lining being casually displaced, but so that it may be readily withdrawn with little effort from the mouthpiece.

In an annular space i afforded between the tapered portions of the members B and C, is arranged the correspondingly tapered absorbent body D. Obviously the said body D may be of any material compatible with 80 its function, and it may be impregnated with a suitable antiseptic or disinfectant by saturation or in other approved manner. When the said body D is positioned between the members B and C, relatively arranged as 85 shown in Fig. 1, it will be manifest that the body will be securely held in proper position and without liability of its being casually displaced. When, however, the member C is turned out of the member B, the absorbent 90 body may be expeditiously and easily removed to be freshly impregnated with disinfectant, after which it may be readily replaced in the member B and secured in position by the illustrated connection of the 95 member C to the member B. It will also be understood that when desired a new body carrying antiseptic or disinfecting material may be substituted for the body shown when occasion demands.

In the practical use of my novel lining, the same may be readily snapped in and on a telephone mouthpiece, and when the lining is arranged as shown in Fig. 1 the disinfectant or antiseptic is enabled to freely pass 105 through the apertures e of the member C and reach all parts of the interior of the mouthpiece.

The elements h constitute important features of my invention and will be appreciated 110

as such when attention is directed to the fact that they serve, because of their fixture to the inner member C, the two-fold function of clamps and finger-pieces, the latter for 5 facilitating the turning of the member C in and out of the member B in connecting and disconnecting the said members. The member C, like the member B, is designed to be made of thin metal, hard rubber or other 10 suitable material, and the body D is preferably of about the proportional thickness shown in Fig. 1, and consequently it will be noted that my novel lining does not form a material obstruction in the mouthpiece A.

15 Having described my invention, what I claim and desire to secure by Letters-Patent, is:

1. A detachable, antiseptic lining for mouthpieces, comprising an outer member, 20 an inner member arranged in and detachably connected to the outer member, and antiseptic means interposed and held between the two members.

2. A detachable, antiseptic lining for 25 mouthpieces, comprising an outer member, an inner member arranged in and detachably connected to the outer member, antiseptic means interposed and held between the two members, and clamps fixed with respect to 30 the inner member, and reaching forwardly, substantially as and for the purpose set forth.

3. A detachable, antiseptic lining for 35 mouthpieces, comprising an outer member interiorly and exteriorly tapered to its forward end and having an exterior shoulder adapted to bring up against the end of a mouthpiece, a correspondingly tapered and foraminous inner member arranged in and 40 detachably connected to the outer member, and antiseptic means interposed and held between the two members.

4. A detachable, antiseptic lining for 45 mouthpieces, comprising an outer member interiorly and exteriorly tapered to its forward end and having an exterior shoulder adapted to bring up against the end of a mouthpiece, a correspondingly tapered and foraminous inner member arranged in and

detachably connected to the outer member, 50 antiseptic means interposed and held between the two members, and clamps fixed with respect to the inner member and reaching beyond the shoulder of the outer member and forwardly, substantially as and for the purpose set forth. 55

5. A detachable, antiseptic lining for mouthpieces, comprising an outer member 60 interiorly and exteriorly tapered to its forward or inner end and having a circumferential flange at its outer or rear end, which flange affords an exterior shoulder and is exteriorly threaded, a correspondingly tapered and foraminous inner member arranged in the outer member and having a forwardly-directed flange at its outer or rear end in 65 which is a thread engaging the exterior thread of the outer member to detachably connect the two members, antiseptic means interposed and held between the two members, and clamps fixed with respect to the 70 inner member and reaching over the flange of the outer member and forwardly beyond said flange.

6. A detachable, antiseptic lining for 75 mouthpieces, comprising an outer member, an inner member detachably secured in the outer member, removable antiseptic means held between the two members, and combined clamps and finger-pieces carried by the inner member. 80

7. A detachable, antiseptic lining for 85 mouthpieces, comprising an outer member, an inner member threaded to the outer member and detachable therefrom, antiseptic means held between the two members, and combined clamps and fingerpieces carried by the inner member and reaching forwardly therefrom, outside the outer member.

In testimony whereof I have hereunto set 90 my hand in presence of two subscribing witnesses.

GEORGE M. SCROGGS.
